DESIGN FOR A DISPLAY CARTON

Frank W. Broderick, New Brighton, N. Y., assignor to Reynolds Metals Company, Richmond, Va., a corporation of Delaware

Application December 30, 1938, Serial No. 82,074

Term of patent 7 years

To all whom it may concern:

Be it known that I, Frank W. Broderick, a citizen of the United States, residing at New Brighton, in the county of Richmond and State of New York, have invented a new, original, and ornamental Design for a Display Carton, of which the following is a specification, reference being had to the accompanying drawing, forming a part thereof, wherein:

Fig. 1 is a perspective view of a display carton showing my design, with the cover of the carton closed;

Fig. 2 is a view similar to Fig. 1, except that the cover of the display carton is open in display position.

I claim:

The ornamental design for a display carton, as shown.

FRANK W. BRODERICK.
